DESIGN FOR A THERMOMETER

Elmer S. Whittier, Bristol, Conn., assignor to The Cooper Oven Thermometer Company, Pequabuck, Conn., a corporation of Connecticut

Application June 4, 1940, Serial No. 92,813

Term of patent 7 years

To all whom it may concern:

Be it known that I, Elmer S. Whittier, a citizen of the United States, residing at Bristol, county of Hartford, State of Connecticut, have invented a new, original, and ornamental Design for a Thermometer, of which the following is a specification, reference being had to the accompanying drawing, forming part thereof.

Fig. 1 is a top plan view showing my new design of a thermometer.

Fig. 2 is a front elevation.

Fig. 3 is a side elevation.

I claim:

The ornamental design for a thermometer, substantially as shown.

ELMER S. WHITTIER.
